SACK HOLDER

Milo Brown, Blackfoot, Idaho

Application April 20, 1936, Serial No. 75,460

3 Claims. (Cl. 248—97)

My invention relates to improvements in sack holders for use particularly in holding sacks in open condition for filling in the field, or elsewhere, as the case may be.

5 The principal object of my invention is to provide an improved light weight, readily portable, and inexpensive device of this character for holding sacks of different sizes in suspended open position and embodying means for holding the mouth of the sack open said means being manipulative to release a portion of the edges of the mouth of a sack while at the same time holding another portion suspended in stretched out condition so that the released portion can be easily 10 and conveniently sewed, or otherwise secured, to the portion being held.

Another object is to provide a device of the character and for the purposes above set forth embodying a base section and a sack clamping and suspending section readily detachable from 20 the base section and attachable to the wall of a barn or warehouse for filling sacks therein.

To the accomplishment of the foregoing, and subordinate objects presently appearing, a preferred embodiment of my invention has been 25 illustrated in the accompanying drawing and described and defined in the following description and claims, respectively.

In said drawing:

30 Figure 1 is a view in perspective illustrating my improved sack holder with the parts of the clamping section in clamping position, and

Figure 2 is a similar view of the clamping section with the clamping parts in releasing position.

35 Referring to the drawing by numerals, the base section 1 of my improved sack support comprises a frame-like structure formed of a single piece of flat bar-like metal bent upon itself to provide a substantially U-shaped bottom part 2 designed to lie flat upon the ground or floor and terminating at its ends in a pair of angularly disposed uprights 3 spaced apart laterally.

40 At the upper ends of the uprights 3 is a clamping section 4 comprising a rectangular plate 5 adapted to be secured at its ends to said ends of the uprights 3, and a pair of brackets 6 extending from the opposite ends of the plate 5, respectively, and including clamping arms 7 extending from the lower edge of the plate 5 horizontally over the bottom part 2 and each terminating in a right angularly related clamping arm 8 bolted to the plate 5 as at 9 the bolts extending through said ends of the uprights 3 and having nuts 10 threaded thereon. A clamping bail 11 is pivotally mounted at its ends on the plate 5 for ver-

tical swinging movement in a pair of bearing members 12 bolted as at 13 to the plate 5 adjacent the arms 8, respectively. The bail 11 comprises a substantially U-shaped portion 14 adapted to overlie the clamping arms 7 for cooperating clamping action therewith and right angularly disposed ends 15 designed for similar cooperation with the clamping arms 8 and terminating in inturned ends 16 journaled in the bearing members 12. The bail 11 is provided along its sides with a plurality of sharp pins 17, preferably a pair on each side, and the clamping arms 7 with correspondingly located apertures 18 for receiving said pins 17. The ends 15 of the bail 11 are each provided with a single pin 19 adjacent the juncture of said arms with the sides of the bail and designed to enter an aperture 20 in the adjacent clamping arm 8 located near the juncture of the arm 8 with its arm 7.

20 In the use of my invention, the bail 11 having been swung upwardly to releasing position a portion of the edge of the sack is stretched across the clamping bars 8 over the apertures 20 therein and the bail 11 lowered into a position in which the pins 19 just pierce said edge portion sufficiently to hold said portion against displacement.

25 In this connection it is to be noted that the construction of the bail 11 and the clamping arms 7 and 8, together with the location of the pins 17 and 19 and apertures 18 and 20 is such

30 that the pins 19 may be entered into the apertures 20 to hold said portion of the sack before the pins 17 enter the apertures 18 in the clamping arms 7. The edge of the sack is next stretched over the clamping arms 7 and the bail 11 fully lowered into clamping position relative

35 to the arms 7, the pins 17 enter in the apertures 18 and securely holding the mouth of the sack open in substantially rectangular shape. By using selected pins 17 and apertures 18 sacks of different sizes may be clamped as described and as will be obvious.

40 When the sack is filled the bail 11 is partially elevated sufficiently to release the edges of the sack from the clamping arms 7 and sides of said bail and without withdrawing the pins 19 from the apertures 20. In this position of the parts the free edge of the sack may be conveniently positioned against the edge portion held by the pins 19 for sewing up or otherwise closing the mouth of the sack.

45 By removing the nuts 10 the clamping section may be detached from the base section 1 and bolted to the wall of a barn or warehouse or any other desired support either by means of the

bolts 9 or by means of bolts inserted in bolt holes 21 provided in the plate 5.

Although certain details of construction have been described in connection with a preferred 5 embodiment of my invention it is to be understood that the present disclosure is illustrative rather than restrictive and that right is herein reserved to modifications of details falling within the scope of the claims appended hereto.

10 What I claim is:

1. In a device of the character described, a base section comprising a U-shaped base having a pair of legs, a pair of spaced apart uprights connected to said legs, and a clamping section 15 secured to said uprights and comprising a pair of brackets, respectively, each including a horizontally disposed arm overlying the corresponding leg of the base and a vertically disposed end arm parallel to the corresponding upright, a bail 20 pivotally mounted intermediate the upright arms and comprising side arms adapted to be swung into clamping relation to said horizontal arms, and right angled end arms adapted to be swung into clamping relation to said upright arms, said 25 bracket arms and bail arms being provided with apertures and pins, respectively, disposed for mating relation.

2. In a device of the character described, a

clamping section adapted to be secured to a support and comprising a pair of brackets, respectively, each including a horizontally disposed arm and a vertically disposed end arm, a bail pivotally mounted intermediate the vertical arms and 5 comprising side arms adapted to be swung into clamping relation to said horizontal arms, and right angled end arms adapted to be swung into clamping relation to said vertical arms, the horizontal bracket arms and the bail side arms being 10 provided with a plurality of apertures and pins, respectively, disposed for mating relation, and related end arms of the brackets and bail being provided with a single aperture and pin, respectively, disposed in mating relation adjacent the 15 juncture of said end arms with the horizontal bracket arms and bail side arms.

3. In a device of the character described, a clamping section adapted to be removably mounted upon a suitable support and comprising 20 cooperating clamping frames one swingable into and out of clamping relation, each frame comprising right angled portions forming in the clamping position of the frames horizontally and vertically clamping jaws, and said jaws being 25 provided with apertures and pins, respectively, disposed for mating relation.

MILO BROWN.
